(57) **CLAIM**

The ornamental design for a LED luminaire, as shown and described.

DESCRIPTION

FIG. 1 is a front view of the LED luminaire of the present invention, in which the broken lines depict portions of the luminaire that form no part of the claimed design;

FIG. 2 is a back view thereof, in which the broken lines depict portions of the luminaire that form no part of the claimed design;

FIG. 3 is a top, back, left perspective view thereof, in which the broken lines depict portions of the luminaire that form no part of the claimed design;

FIG. 4 is a top, back, right perspective view thereof, in which the broken lines depict portions of the luminaire that form no part of the claimed design;

FIG. 5 is a left view thereof, in which the broken lines depict portions of the luminaire that form no part of the claimed design;

FIG. 6 is a right view thereof, in which the broken lines depict portions of the luminaire that form no part of the claimed design; and,

FIG. 7 is a front downward perspective view thereof, in which the broken lines depict portions of the luminaire that form no part of the claimed design.

The broken line areas in the Figures show environmental subject matter and other disclaimed subject matter, and form no part of the claimed design.

1 Claim, 7 Drawing Sheets
